UNITED STATES PATENT OFFICE.

CHARLES B. HUESTIS, OF UKIAH, CALIFORNIA.

SHINGLING-SEAT.

SPECIFICATION forming part of Letters Patent No. 354,703, dated December 21, 1886.

Application filed June 30, 1886. Serial No. 206,750. (No model.)

To all whom it may concern:

Be it known that I, CHARLES B. HUESTIS, of Ukiah, Mendocino county, State of California, have invented an Improvement in 5 Shingling-Seats; and I hereby declare the following to be a full, clear, and exact description of the same.

My invention relates to a seat and nail holder to be employed by workmen in putting shingles upon sloping roofs.

It consists in the construction and combination of devices which I shall hereinafter fully describe and claim.

Referring to the accompanying drawings 15 for a more complete explanation of my invention, Figure 1 is a perspective view of the device. Fig. 2 is a view of the parts separated.

A is a frame, which may be made of steel or iron bars, and it has a seat, B, made of 20 wood, which is secured to it by bolts or screws. At one end the frame or side bars, A, are hinged to the ends of other bars, C, which form a shoe at D. This shoe is provided with teeth or points E, which are made sloping or 25 inclined, so as to enter the surface of the roof upon which it is placed, thus holding the whole firmly and preventing it from slipping.

The rear ends of the side bars, A, have curved segments F, extending downward, and similar 30 curved segments, G, extend upward from the shoe C, so as to form a continuation of the curved segments F. The segments F and G overlap each other and have slots, holes, or perforations by which they may be united together at any point by bolts or otherwise, so 35 that the angle between the bars A and the shoe C may be made greater or less for the purpose of holding the seat B level upon any incline or pitch of roof that it may be employed 40 upon. H are braces, which extend upward from the rear ends of the shoe-bars C, and serve to support the curved arms G.

Upon the side of the seat B is fixed a nail-box, I, which is made of any suitable material, sheet-iron being very suitable for this 45 purpose. This box is secured upon one side of the seat, as shown, so as to be conveniently within reach of the operator.

This seat differs from what is known as the 50 "shingling-bracket," as it is independent and movable to any point which may be desired by

the operator, while the bracket simply serves to support one portion of a long board or staging, which is supported by a number of brackets, and is stationary at whatever point it may 55 be fixed.

With my device the operator may move as the work progresses from point to point, having everything necessary for his work with him, and is not dependent upon any fixed 60 staging.

I am aware a shingling-bracket has been formed of two sections hinged together at their front ends, one of said sections having teeth or projections and a curved segment passing 65 through a slot or opening in the rear end of the upper section. I am also aware it is not broadly new to adjust the angle between the sections of a shingling-bracket by means of a pin passing through openings in a segment or 70 arm projecting from one of said sections, and such construction I therefore do not broadly claim as my invention.

Having thus described my invention, what I claim as new, and desire to secure by Letters 75 Patent, is—

1. The bars C, provided with the inclined or sloping points E, and the perforated curved segments G, in combination with the bars A, hinged at their front to the bars C, and having 80 perforated curved segments forming a continuation of the segments G, and the seat B, secured upon the bars A, substantially as herein described.

2. An improved shingling-seat comprising 85 the combination of the bars A and C, hinged together at their front portions, and having overlapping and perforated curved segments at the rear, suitable inclined or sloping teeth formed in the bars C, the braces H, for supporting the curved segments G, the seat B, and the holder or box formed with or projecting from one side of the seat, all constructed and arranged to operate substantially as herein 90 described.

In witness whereof I have hereunto set my hand.

CHARLES B. HUESTIS.
